(57) CLAIM

The ornamental design for a “wall mounted tape measure”, as shown and described.

DESCRIPTION

FIG. 1 is a front elevation view of the tape measure for wall mounting according to the present invention;

FIG. 2 is a side view of the invention (the opposite side being a mirror image thereof);

FIG. 3 is a top plan view of the invention;

FIG. 4 is a perspective view of the invention;

FIG. 5 is a front elevation view of a second embodiment of the present invention of FIG. 1, the only difference being the lack of a circular back plate;

FIG. 6 is a side view of the second embodiment of the invention (the opposite side being a mirror image thereof);

FIG. 7 is a top plan view of the second embodiment of the invention; and,

FIG. 8 is a perspective view of the second embodiment of the invention.
